CLAIM

The ornamental design for a battery charger for a controller, as shown and described.

DESCRIPTION

FIG. 1 is a perspective view of a first embodiment of a battery charger for a controller showing our new design;

FIG. 2 is a front elevation view of the first embodiment;

FIG. 3 is a rear elevation view of the first embodiment;

FIG. 4 is a left side view of the first embodiment;

FIG. 5 is a right side view of the first embodiment;

FIG. 6 is a top plan view of the first embodiment;

FIG. 7 is a bottom plan view of the first embodiment;

FIG. 8 is a referential perspective view of the first embodiment for showing a used state, the rested controller is shown in broken lines forming no part of the claimed design; and,

FIG. 9 is another referential perspective view of the first embodiment for showing a state when two battery chargers are connected, one of battery chargers connected is shown in broken lines forming no part of the claimed design.

The broken lines showing portions of the battery charger for a controller in the drawings are included for the purpose of illustrating environmental structure and form no part of the claimed design.
